UNITED STATES PATENT OFFICE.

JOHN ROTH, OF JERSEY CITY HEIGHTS, NEW JERSEY.

DIE.

No. 820,603.

Specification of Letters Patent.

Patented May 15, 1906.

Application filed March 11, 1905. Serial No. 249,567.

To all whom it may concern:

Be it known that I, JOHN ROTH, a subject of the German Emperor, residing in Jersey City Heights, in the county of Hudson and 5 State of New Jersey, have invented certain new and useful Improvements in Dies, of which the following is a specification.

In making cast-metal dies for stamping ornamental metallic articles the die is usually 10 cast in one block of steel or other metal. This is objectionable, for the reason that the more delicate impressions in the die are not reproduced clearly and have to be finished by hand before using the die and that the die being 15 cast in one block has small defects in its surface and is expensive, owing to the large quantity of metal required for the same.

The object of my invention is to furnish an improved die or mold in which the body of 20 the die-block is made of cheaper metal, while the die proper is cast in a separate piece of harder metal and secured into the die-block, so that the same form one structure. This permits the casting of a die with all the delicate 25 impressions of the article to be produced by the same, reduces the expense of the die material, and furnishes much better and more ornamental impressions.

With these ends in view the invention consists 30 in the novel features and combinations of parts, to be hereinafter described and claimed.

In the accompanying drawings, Figure 1 is a perspective view of my improved die, 35 and Fig. 2 is a vertical central section of Fig. 1.

Similar letters of reference indicate corresponding parts.

In making my improved die the main portion or body B of the die-block is made of 40 cheaper metal and provided in its top surface with a recess which corresponds to the general shape of the die D, that is to be used in connection with the die-block B, and said 45 recess is provided with small sockets or cavities, as shown. The die D is cast separately from the main portion B, with the proper ornamentation on the face of the same, so as be used for stamping the ornamental articles 50 from the same, and provided at its under

side with projections or with small cavities or sockets. The under side of the die corresponds with the recess in the top of the die-block B, so as to leave a space between the same, which for attaching the die D to the 55 block B is filled up with metal m through a casting-hole at one point of the circumference of the die, as at t in Fig. 1, so as to fill the cavity between the die-block and die and all the small cavities in order to form a connected structure between the die-block and die. The upper edge of the die proper, however, abuts throughout the perimeter of the same, except at the casting-hole t, against that of the recess in the die-block, so that the fusible 60 metal does not extend quite to the upper surface of the die-block, and therefore forms no part of the upper surface of the die structure. The circumference of the die D is preferably provided with an undercut, so as to 65 provide a means for firmly holding the die in the die-block B.

The die D being of even thickness and smaller in size remains true to its shape and reproduces all the finer parts of the original, so 70 that but little hand-work is required for completing the same. It is made of superior metal or alloys—such as nickel-steel, aluminum or silicium bronze, and the like—by which a more durable die is obtained and by 75 which the ornamentation can be reproduced in the article to be stamped by the die in a superior manner. When the die-block and die are united into one structure by the intermediate layer of cast metal, the die is ready 80 for use. As the die-block is made of cheaper metal, the die can be furnished at much less expense than the dies heretofore in use. It possesses a forming-surface of superior quality by which the ornamental articles can be 85 stamped out in a quicker and more satisfactory manner than by the ordinary cast dies heretofore in use.

Having thus described my invention, I claim as new and desire to secure by Letters 90 Patent—

A die comprising a die-block provided with a top recess, a die proper seated in said recess and abutting at its upper side edge substantially throughout its perimeter against the 95 100

upper edge of said recess, said die being undercut at its circumference, and a layer of fusible metal between the side and bottom of said die and the side and bottom of said 5 recess for uniting said die and die-block in one structure.

In testimony that I claim the foregoing as

my invention I have signed my name in presence of two subscribing witnesses.

JOHN ROTH.
